[57] **CLAIM**

The ornamental design for a portable solvent recovery apparatus, as shown and described.

DESCRIPTION

FIG. 1 is a top, front and right side perspective view of a portable solvent recovery apparatus showing my new design;

FIG. 2 is a front elevational view thereof;

FIG. 3 is a right side elevational view thereof;

FIG. 4 is top plan view thereof;

FIG. 5 is a rear elevational view thereof;

FIG. 6 is a left side elevational view thereof; and

FIG. 7 is a bottom plan view thereof.

The hose in FIGS. 1, 2, 3, and 5 is shown broken away for ease of illustration.

Fig.1.

Fig.2.
